ATTORNEY.

UNITED STATES PATENT OFFICE.

ANTHONY T. BOLTAS, OF PLAINFIELD, NEW JERSEY.

ELECTRIC APPARATUS.

1,356,484.

Specification of Letters Patent. Patented Oct. 19, 1920.

Application filed August 19, 1919. Serial No. 318,609.

To all whom it may concern:

Be it known that I, ANTHONY T. BOLTAS, a citizen of the United States, residing at Plainfield, in the county of Union and State 5 of New Jersey, have invented new and useful Improvements in Electric Apparatus, of which the following is a specification.

This invention relates to an apparatus for producing or stimulating rain fall by the 10 coaction of the atmospheric electricity and machine made electricity connected to act in conjunction with static charges in the earth.

An object of the invention is to provide 15 electrical discharge means so mounted that the position thereof may be changed according to the direction of travel of atmospheric currents so that a greater action may be accomplished between my machine 20 and the atmospheric electricity.

An object of the invention is to provide an apparatus by means of which current may be discharged into the air and besides bring about coaction between the electricity 25 of the earth and that traveling in the air.

With these and other objects in view the invention will be better understood from the following detail description taken in connection with the accompanying drawing 30 wherein:

Figure 1 is a side elevation of the wheel.
Fig. 2 is a front elevation of the wheel.

Fig. 3 is a diagrammatic view.

Referring to the drawing illustrating one 35 of the many forms in which my invention may be constructed the numeral 1 designates a tower or platform upon which is mounted the turning table 2. This turn table 2 rotatably supports the shaft 3 that has a driving 40 connection 4 with an electric motor 5 upon the platform. Secured to the shaft is a discharge wheel 6 that consists of a conducting ring 7 from which radiates a large number of pointed rods 8. The ring 7 is supported 45 on a disk of insulating material 9 that is in turn directly secured to the shaft. Bearing upon the ring 7 is a brush 10 forming one terminal for the conductor 11 in which is

arranged a source of current 12. The other terminal of this conductor is connected to 50 a plate 13 that is embedded in the earth.

It is of course to be understood that if found necessary in practice or is advantageous the source of current may be dispensed with and the static charge of the 55 earth relied on to discharge current into or receive current from the air. It is of course to be understood that to bring about the discharge from the rods the potential difference between the atmospheric electricity and the charge of the earth must be great enough to overcome resistance. As soon as the proper discharge takes place and the potential difference is about neutral rain fall will be produced. 65

What I claim is:—

1. An electric apparatus comprising a tower, a discharge wheel supported thereby and means for driving and feeding current to said wheel. 70

2. An electric apparatus comprising a tower, a discharge wheel supported thereby and provided with numerous discharge points and means for driving and feeding current to said wheel. 75

3. An electric apparatus comprising a tower, a discharge wheel supported thereby and provided with numerous discharge points and means for driving and feeding current to said wheel, and a turn table for 80 the wheel whereby the position thereof may be changed according to the direction of travel of the electrified air.

4. An electric apparatus comprising a tower, a turn table mounted thereon, a shaft 85 rotatably supported by the turn table, means for rotating the shaft and a wheel supported on the shaft consisting of a current conducting disk and a plurality of pointed rods radiating therefrom and electrically 90 connected to the disk, and means for connecting the disk to a source of current and to the earth. 95

In testimony whereof I affix my signature.

ANTHONY T. BOLTAS.
